MILLARD C. EISEMAN AND GEORGE A. BEILFUSS, OF CHICAGO, ILLINOIS

COMBINATION RAZOR AND GUARD

Application filed January 5, 1931. Serial No. 506,677.

Our invention relates to razors and more particularly it relates to improvements providing an adjustable safety device or guard for razors of the type which have a folding 5 blade and handle and are generally designated as common razors. It is well-known that such razors are frequently in use for long periods of time and that as a result of long usage the blades are sometimes worn 10 away a substantial amount. The efficiency of such a razor in many cases increases with age and use either actually or in the opinion of the owner and the use of such a razor is, for that reason, continued as long as possible.

15 The use of a safety guard with common razors has not been extensively adopted and among the various reasons for not doing so may be named the interference of the guard with the efficient use of the razor after the 20 blade becomes worn and also because of the inconvenience of detaching and attaching the guard to the blade for the purpose of sharpening and cleaning the razor. Safety guards as heretofore constructed for common 25 razors have been given a fixed position relative to the back of the blade and as the blade becomes narrower by use the distance between the cutting edge of the blade and the edge of the guard diminishes to such an extent 30 that the guard interferes with and prevents efficient operation of the razor. When this stage of wearing away of the blade has been reached the razor must either be used 35 without a guard, or a narrower guard provided, or the razor be entirely discarded.

An object of the invention is the provision of an improved safety guard for common razors including means permitting a positive 40 adjustment of the guard to compensate for small increments of wear of the razor blade by enabling the guard to be shifted and spaced from the cutting edge and maintained at a constant distance therefrom correspond- 45 ing to the most advantageous and efficient use of the razor.

A further object of the invention is the provision of a razor blade of the kind described which is provided with end extensions 50 cooperating with a casing to form a guard

which is easily removed in order that the razor may be cleaned and sharpened.

Still another object is the provision of an improved guard for common razors which permits the razor to be used effectively with 55 either side next to the face in the same manner as if no guard were in use.

A further object is to generally improve common razors of the kind described.

A still further object of the invention is to 60 provide a guard in combination with a common razor which is simple, durable, reliable, efficient and satisfactory for its intended purpose.

Many other objects and advantages of the 65 construction herein shown and described will be obvious to those skilled in the art from the disclosure herein given.

To this end our invention consists in the 70 novel construction, arrangement and combination of parts herein shown and described, and more particularly pointed out in the claims.

In the drawings wherein like reference 75 characters indicate like or corresponding parts,

Fig. 1 is a perspective view of a common 80 razor equipped with a guard embodying the principles of our invention;

Fig. 2 is a section along the line 2—2 of 85 Fig. 1;

Fig. 3 is a view along the line 3—3 of 90 Fig. 2;

Fig. 4 is a sectional view along the line 95 4—4 of Fig. 3;

Fig. 5 is a sectional view along the line 100 5—5 of Fig. 3;

Fig. 6 is an end view of a detail of a razor 105 blade embodying the principles of our invention;

Fig. 7 is a sectional view along the line 110 7—7 of Fig. 1 drawn to a larger scale; and

Fig. 8 is a large scale detail view of a 115 portion of the device.

Referring now more particularly to the 120 drawings, the numeral 10 designates a common razor blade having handle members 11 attached thereto by a pivot 12. Tapered side walls 13 connected by end walls 14 and 15 form a casing providing a guard for the 125 100

blade 10. One of the side walls 13 is hinged-
ly mounted on the end wall 14 by a pivot
connection 16 and is detachably fastened to
the end wall 15 by a latch pin 17. The wall
15 contains an aperture 18 in which the pin
17 is positioned when the casing is closed.
A stem 19 on the end wall 15 provides means
for moving the free end of the wall 15 out-
wardly to engage and disengage the pin 17
10 with the wall 15 in the process of attaching
and detaching the casing from the blade 10.
The walls of the casing are preferably formed
from thin light sheets of metal of sufficient
rigidity to insure that the casing will stay in
15 position on the blade and function properly
as a guard and yet have the necessary resili-
ency to permit yielding of the end wall 15
when pressure is exerted on the stem 19 for
that purpose.

20 The blade 10 is provided with end exten-
sion members 20 and 21, preferably of uni-
form thickness, in order that the position
of the casing may be shifted relative to the
cutting edge of the blade. The end extension
25 members 20 and 21 are respectively provided
with a plurality of serrations 22 and 23.
The ends of the casing have inwardly pointed
projections 24 and 25 which are respectively
engageable with any one of the adjacent ser-
20 rations 22 and 23 when the casing is mounted
on the blade 10. The pointed projections 24
and 25 hold the casing against movement
longitudinally of the blade 10 and also
against movement in the direction of the
35 width of the blade. The cutting edge of the
blade 10 projects from between the converg-
ing edges of the side walls 13 in an amount
sufficient to permit the blade to perform its
function efficiently with the side walls 13 serv-
40 ing as guards eliminating the danger of
gashing or cutting the face. As the blade 10
is gradually worn away the casing may be
moved towards the back of the blade by posi-
tioning the projections 24 and 25 in the next
45 adjacent serrations in the direction of the
back of the blade. The spacing of the ser-
rations is relatively small and thereby per-
mits slight adjustments to compensate for
the wear of the blade by maintaining a sub-
50 stantially uniform spacing between the
cutting edge of the blade and the walls 13.

Any tendency to lateral movement of the
casing on the blade 10 is prevented by pro-
viding inwardly projecting members 26 and
55 27 at the hinged end of the casing and similar
projecting members 28 and 29 at the latch end
of the casing. The inwardly projecting
members 26 and 27 have their inner faces
parallel when the casing is closed and spaced
60 apart a distance corresponding to the thick-
ness of the end extension 20 of the blade 10.
Similarly the inwardly projecting members
28 and 29 have their inner faces parallel and
spaced apart sufficiently to engage the side
65 walls of the end extension 21 of the blade 10.

By this arrangement the inner faces of the
projecting members 26 and 27 and of the
projecting members 28 and 29 are in close con-
tact and in holding engagement with the
blade 10 for all adjusted positions of the
70 casing and prevent any lateral movement
relative to the blade.

The end wall 15 of the casing preferably
terminates at its forward end in alignment
75 with the corresponding edges of the side walls
13 and stops short at its outer end a substan-
tial distance to permit the casing to be shift-
ed a substantial amount backwardly on the
blade without interference with the handle
80 portion of the blade.

Thus it will be seen that we have provided
a guard casing for the blade of a common
razor which forms an adjustable mounting to
compensate for the wear of the blade and
which holds the casing in all adjusted posi-
85 tions against any movement relative to the
blade.

Having thus described our invention, it is
obvious that various immaterial modifica-
tions may be made in the same without de-
parting from the spirit of our invention;
hence, we do not wish to be understood as
limiting ourselves to the exact form, con-
struction, arrangement and combination of
parts herein shown and described or uses
95 mentioned.

What we claim as new and desire to se-
cure by Letters Patent is:

1. In combination, a razor blade, a casing
forming a guard for the blade, adjusting
means permitting the casing to be shifted to
compensate for the blade becoming narrower
by reason of wear, said means comprising end
100 extension members of uniform thickness and
each having a plurality of end serrations,
said casing comprising side walls hingedly
connected at one end and having detachable
fastening means at the other end, a projection
105 at each end of the casing so positioned as to
selectively engage any one of the adjacent
serrations, and means preventing lateral
movement of the casing relative to the blade,
said last mentioned means comprising spaced
110 apart projecting members on the inside faces
of the casing so positioned as to engage the
side walls of said extensions for all adjusted
positions of the casing.

2. In combination, a razor blade, a casing
forming a guard for the blade, adjusting
means permitting the casing to be shifted to
compensate for the blade becoming narrower
by reason of wear, said means comprising end
120 extension members of uniform thickness
each having a plurality of serrations, said
casing comprising side walls hingedly con-
nected at one end and having detachable fas-
tening means at the other end, a projection
125 on the inner face of said casing at each end
so positioned as to selectively engage any
one of the adjacent serrations, and spaced
130

apart projecting members on the inside faces
of the casing so positioned as to engage the
side walls of said extensions for all adjusted
positions of the casing to prevent lateral
5 movement of the casing relative to the blade,
the cutting edge of the blade projecting from
the casing for all positions of the casing.

In witness whereof, we hereunto subscribe
our names this 2nd day of January, A. D.
10 1931.
